UNITED STATES PATENT OFFICE.

FRANK P. D'ARCY, OF KALAMAZOO, MICHIGAN.

CUSHION STRUCTURE.

1,285,063.

Specification of Letters Patent. Patented Nov. 19, 1918.

Application filed March 1, 1916. Serial No. 81,485.

To all whom it may concern:

Be it known that I, FRANK P. D'ARCY, a citizen of the United States, residing at Kalamazoo, county of Kalamazoo, State of Michigan, have invented certain new and useful Improvements in Cushion Structures, of which the following is a specification.

This invention relates to improvements in cushion structures.

10 The main objects of this invention are:

First, to provide in a spring cushion structure an improved means for securing the upholstery cover to the spring supporting frame.

15 Second, to provide an improved spring cushion structure in which the springs may be mounted completely upon their supporting frame and the upholstery securing frame formed independently and quickly assembled 20 upon the spring structure.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated in 30 the accompanying drawing, forming a part of this specification, in which:

Figure I is a detail perspective view of my improved spring cushion structure, a portion only of the springs being shown and 35 the upholstering being omitted.

Fig. II is an enlarged detail vertical section through a completed structure embodying the features of my invention.

Fig. III is a perspective view of the upholstery frame.

Fig. IV is an enlarged detail vertical section on a line corresponding to line 4—4 of Fig. III, showing structural details.

Fig. V is a detail section on a line corresponding to line 5—5 of Fig. III, showing further structural details.

Fig. VI is a detail plan view of a slightly modified construction of the upholstery frame.

50 Fig. VII is a detail vertical section corresponding to that of Fig. IV of another modified form of my invention, the modification

being in the manner of securing the upholstery covering.

In the drawing, similar reference characters refer to similar parts throughout the several views, and the sectional views are taken looking in the direction of the little arrows at the ends of the section lines.

Referring to the drawing, the springs 1 are of the double helically coiled type and are provided with top and bottom supports. These supports, in the structure illustrated, are substantial duplicates so that a description of one will suffice. The spring support 5 comprises the border frame 2 formed of wire and the supporting wires 3 arranged in crossed sets, the ends of the wires being secured at 4 by wrapping the wires around the border frame. The support wires 3 are 10 arranged in pairs and provided with offsets 5 which engage the top and bottom coils of the springs, the offsets being of such length that their ends, which form shoulders 6, engage the outer sides of the coils. The offsets are 15 provided with reversely projecting loops 7, that is, the loops project in the direction opposite from that of the offsets. These loops are arranged centrally of the offsets and disposed on the inside of the coils. The support wires are locked to the coils by means of the locking wires 8, which are threaded 20 through the loops on the side of the coils opposite the offsets so that the coils are locked within the offsets and being engaged 25 by the offsets, as described, are supported against any lateral or sliding movement on their support wires as well as being supported in an upright position.

The upholstery attaching frame 9 is 30 formed of sheet metal and is channel-shaped in cross section to receive the tacking strip 10. The upholstery frame 9 is provided with flanges 11 and 12 at its edges which are clamped upon the tacking strip. The lower 35 flange 12 is in the form of a bead to provide a finish and to protect the edges of the covering 13. The upholstery comprises an inner cover 14, the filler 15 of hair or suitable material, and the outer cover 13. The 40 upholstering may be tufted or otherwise, as desired.

The edges of the covering are secured to the upholstering frame 9 by means of the

2
tacks 16. A finishing strip or "gimp" 17 is preferably provided. The tacks are driven into the tacking strip and are preferably of such length that they engage the back of the 5 channel and are turned or clenched. The upholstery frame is slipped over the spring border frame 2 and secured thereto by means of the tongues 18 which are struck out of the upholstery frame and clamped over the 10 cushion frame 2, as shown in Fig. IV. This enables the convenient and quick assembling of the parts.

It is found that even when the tacking strips are formed of very high grade wood 15 especially adapted for the purpose a considerable proportion of them split at the corners when bent to form or afterward when they dry out. To prevent this and to effectively support the tacking strips at the 20 corners I provide the perforated corner strips 19 which are arranged over the tacking strips and engaged and retained by the flanges of the upholstering frame, being clamped by the flanges so that they are securely held in place against the tacking strips. The perforations permit the driving 25 of tacks for securing the covering around the corners of the frame. These corner strips also serve to protect the tacking strips 30 from the edges of the bottom flange 12 which tends to split them when the frame is bent up, it being the practice to secure the tacking strip in the channel and then bend or form the same.

35 The end 20 of the tacking strip is arranged to lap the joint 21 of the upholstery frame 9 (see Fig. III), and serves as a suitable connection between these parts.

In the modified structure shown in Fig. 40 VI the upholstery frame is formed in sections 22 and 23 connected by the coupling sleeves 24, there being some spring constructions in which the upholstery frame shown in Fig. III cannot be conveniently positioned after the upholstery has been attached thereto. By forming the frame in sections as shown in Fig. VI, the sections can be swung apart to permit the arrangement of the upholstery on the springs and joined together and secured to the frame of the 45 spring support and after being so secured are retained in their closed relation. The sections can be formed in the flat and bent up as they are applied, if desired.

50 In the modification shown in Fig. VII, the upholstering frame 25 is provided with an upwardly facing channel 26 at its lower end adapted to receive the edge of the skirt 27 of the covering after the same has been folded over the beading or edge wire 29.

The outer edge of the channel is clamped upon the edge of the covering with the bead wire or cord therein effectively securing it in position.

55 Tongues 18 are struck out from the up-

holstering frame to engage the spring supporting frame as in the preferred construction.

My improved cushion structure is simple and economical to produce. The covering 70 may be quickly and easily secured and the structure is attractive and finished in appearance.

I have not attempted to illustrate or describe certain modifications which I contemplate as I believe the disclosure made will enable those skilled in the art to which my invention relates to embody or adapt the same as conditions may require.

Having thus described my invention, what 80 I claim as new and desire to secure by Letters Patent, is:

1. In a spring cushion, the combination of the springs, a support therefor comprising a frame, an upholstery frame channel-shaped 85 in cross section and provided with flanges at its edges, the bottom flange being bead-like in form, said upholstery frame being arranged to embrace said spring frame and provided with integral tongues engaging therewith whereby the frames are secured together, a tacking strip arranged and retained in said upholstery frame channel by its said flanges, perforated corner strips arranged over said tacking strip at the corners of said upholstery frame and engaged and retained by the said flanges thereof, and a covering secured to said upholstery frame by tacks driven into said tacking strip.

2. In a spring cushion, the combination of 100 the springs, a support therefor comprising a frame, an upholstery frame channel-shaped in cross section and provided with flanges at its edges, the bottom flange being bead-like in form, said upholstery frame 10 being arranged to embrace said spring frame and provided with integral tongues engaging therewith whereby the frames are secured together, a tacking strip arranged and retained in said upholstery frame channel by its said flanges, and a covering secured to said upholstery frame by tacks driven into said tacking strip.

3. In a spring cushion, the combination 11 of the springs, a support therefor comprising a spring frame, an upholstery frame channel-shaped in cross section and provided with flanges at its edges, said upholstery frame being arranged to embrace said spring frame and secured thereto, a tacking strip arranged and retained in said upholstery frame channel by its said flanges, and corner strips arranged over said tacking strip at the corners of said upholstery frame and engaged and retained by the said flanges thereof.

4. In a spring cushion, the combination 12 of the springs, a support therefor comprising a spring frame, an upholstery frame channel-shaped in cross section and pro-

vided with flanges at its edges, said upholstery frame being arranged to embrace said spring frame and secured thereto, and a tacking strip arranged and retained in said upholstery frame channel by its said flanges, the edges of which are folded upon the face of the strip.

5. In a spring cushion, the combination of the springs, a support therefor comprising a spring frame, an upholstery frame channel-shaped in cross section arranged to embrace said spring frame and provided with integral tongues engaging therewith whereby the frames are secured together, a tacking strip clamped in said upholstery frame channel, and corner strips clamped over said tacking strip at the corners of said upholstery frame.

6. In a spring cushion, the combination of the springs, a support therefor comprising a spring frame, an upholstery frame channel-shaped in cross section arranged to embrace said spring frame and provided with integral tongues engaging therewith whereby the frames are secured together, and a tacking strip clamped in said upholstery frame channel.

7. In a spring cushion, the combination of the springs, a support therefor comprising a spring frame, an upholstery frame arranged to embrace said spring frame and provided with integral securing tongues engaging therewith, and a tacking strip carried by said upholstery frame.

8. In a cushion, the combination of an upholstery frame channel-shaped in cross section and provided with flanges at its edges,

a tacking strip arranged and retained in said upholstery frame channel by its said flanges, and corner strips arranged over said tacking strip at the corners of said frame and engaged and retained by the said flanges thereof.

9. In a cushion, the combination of an upholstery frame channel-shaped in cross section, a tacking strip clamped in said upholstery frame channel, and corner strips clamped over said tacking strip at the corners of said frame.

10. In a seat, the combination with a spring frame and a cushion provided with a depending skirt, of a skirt frame formed of a metallic channel bar having portions struck out from the web thereof to form upturned hooks for engaging with the base of the spring frame, and a wooden insert in said channel bar to which said skirt is tacked.

11. In a seat, the combination with a spring frame and a cushion provided with a depending skirt, of a skirt frame formed of a metallic bar having flanges with portions struck out to form upturned hooks for engaging with the base of the spring frame, and a wooden member engaging said metallic bar to which said skirt is tacked.

In witness whereof I have hereunto set my hand and seal in the presence of two witnesses.

FRANK P. D'ARCY. [L.S.]
